SUSPENDING ARRANGEMENT FOR
CURTAINS

Karel Tomášik, Vsetin, Czechoslovakia

Application February 1, 1949, Serial No. 73,903

3 Claims. (CL. 16—87.6)

1

This invention relates to suspending arrangement for window curtains including roller mounted suspension means with readily attachable curtain gripping jaws by which the curtain is supported for easy and convenient manipulation to cover or clear the window opening.

Heretofore many different proposals have been made for hanging curtains on supporting rods or tracks, but most of these have required attachment of the curtain to suspension means mounted at the top of the window-frame or involved use of rods upon which the curtain is threaded and then rung in place. Previous devices have also presented other inconveniences and disadvantages in that the securing means tend to tear the curtain or grip the same insecurely so that it easily pulls from the fastenings.

The present invention eliminates the disadvantages of the prior art devices, both as to convenience in hanging the curtains and secure gripping thereof without danger of tearing, by providing a suspension arrangement including spring closed gripping jaw members which are individually attached to the curtain and individually separably engaged with suspension members slidably supported by a head rod or track.

The details of construction of the suspension arrangement according to the invention will be apparent by reference to the following detailed specification and the accompanying drawings forming a part thereof and in which:

Fig. 1 is a section through a supporting track with a suspension arrangement embodying the invention mounted therein, parts of the latter being in section.

Fig. 2 is a front elevation of a suspended member removed from the track.

Fig. 3 is a side view thereof.

Fig. 4 is a vertical section through the gripping jaws on line 4—4 of Fig. 1, and

Fig. 5 is a vertical section on the line 5—5 of Fig. 4.

Referring now more particularly to the drawings, 1 is a supporting bracket adapted to be secured to the top of a window frame and including a box section track 2 having a central slot 3 in the bottom wall thereof. The suspension members each consist of a pair of rollers 4 within the track 2 connected by an axle pin 5 on which a plate-like suspension member 6 is hung so as to extend through the slot in the track. The suspension plate is provided on opposite sides with horizontal grooves 7 and is tapered below the grooves as indicated at 8.

Individual curtain clamping members are pro- 55 the like comprising a pair of jaw members piv-

2

vided, each consisting of a pair of jaw members 9, preferably of channel shape in cross section and formed with overlapping ears 10 pivoted together by a pivot pin 11. The jaw members 9 are formed with curtain gripping lower ends 12 between which the upper edge of the curtain is clamped. The lower ends 12 of the jaws 9 are resiliently held together by flat spring members 13 disposed within the channel shaped jaws and having one end thereof secured to the jaws adjacent the lower end thereof such as by passing the end of each spring through a slot 14 in the bottom wall of the channel forming the jaws, well below the pivot 11.

15 Each of the spring members 13 extends upwardly within the jaws to a point above the pivot 11 where they are curved inwardly toward each other to form reentrant curves 15 in opposed confronting relation centrally above the pivot 11 so as to bear against the groove 7 and bias the jaws to closed position.

The curtain clamping members are detachably secured to the suspending members by forcing the tapered end 8 of the depending plate 6 between the inturned upper ends 15 of the springs 13 until the latter snap into the grooves 7.

In the use of the arrangement, the required number of gripping members are clamped along the upper edge of the curtain to be hung by pressing the upper ends of the jaws together to spread the lower gripping ends which are slipped over the edge of the curtain to grip the same between them when the upper ends are released. The curtain is then hung by pushing the gripping members against the lower edges of the suspension plates to engage the latter between the upper ends of the springs, as previously described, the grip of the springs in the grooves 7 being sufficient to resist separation by any ordinary pull on the curtain. The spreading of the upper ends of the springs by the plates 6 also increases the closing tension of the springs on the lower ends of the jaws, thereby tightening the grip thereof on the curtain which has previously been inserted between them.

While a preferred embodiment of the invention has been shown and described by way of illustration, it will be understood that variation in the details of construction of the parts may be resorted to without departing from the spirit of the invention within the scope of the appended claims.

I claim:

1. Suspending arrangement for curtains and the like comprising a pair of jaw members piv-

oted together and forming curtain gripping elements below the pivot, a flat elongated spring member secured at one end to each of said jaw members below the pivot thereof, each spring member extending above the pivot and curved inwardly into opposed confronting relation with respect to the other to bias the jaws to closed position, and a suspension member having a depending portion engaged between the confronting portions of the spring members to mount the jaw members on said suspension member and increase the closing tension of the springs on the jaws.

2. Suspending arrangement for curtains and the like comprising a pair of jaw members pivoted together and forming curtain gripping elements below the pivot, a flat elongated spring member secured at one end to each of said jaw members below the pivot thereof, each spring member extending above the pivot and curved inwardly into opposed confronting relation with respect to the other to bias the jaws to closed position, and a suspension member having a depending portion provided with a head at the lower end thereof engaged between the confronting portions of the spring members to mount the jaw members on said suspension member.

3. Suspending arrangement for curtains and the like comprising a pair of jaw members piv-

oted together and forming curtain gripping elements below the pivot, each of said jaw members being of channel form in cross section, a flat elongated spring member having one end engaged through a slot in the bottom of the channel portion of each of said jaw members, each of said spring members extending above the pivot and having a coiled upper end portion disposed in opposed confronting relation with respect to the other for biasing the jaws to closed position, and a suspension member having a depending head portion resiliently clamped between the confronting coiled portion of said spring members to releasably mount said jaw members on said suspension members.
